SIGNALING DEVICE FOR INDICATING FIRES
OR HIGH-TEMPERATURE CONDITIONS IN
ROOM AREAS

Albert O. Kjeldergaard, Bejou, Minn.

Application July 8, 1949, Serial No. 103,696

9 Claims. (Cl. 116—106)

1

This invention relates to new and useful improvements in signaling devices and the primary object of the present invention is to provide a device for indicating fires or high temperature conditions in a furnace room or selected room areas of commercial or domestic building establishments.

Another important object of the present invention is to provide a signaling device including a spring operated alarm having a braking mechanism and a means responsive to high temperature conditions for releasing the braking mechanism whereby the alarm will be sounded.

A further object of the present invention is to provide a signaling apparatus embodying a spring operated alarm having a finger grip that will rotate during the sounding of the alarm and novel and improved means operated during the rotation of the finger grip for actuating a further alarm.

A still further aim of the present invention is to provide a fire alarm that is small and compact in structure, strong and reliable in use, efficient and durable in operation, quickly and readily installed and serviced, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the present invention installed and ready for use;

Figure 2 is a perspective view of the present invention, the hood removed therefrom;

Figure 3 is a perspective view of the thermal responsive member used in conjunction with the present invention, the dust shield removed therefrom;

Figure 4 is a vertical sectional view taken substantially on the plane of section line 4—4 of Figure 2 and showing the pivotal member as holding the swingable member against the base;

Figure 5 is a view similar to Figure 4 and showing the swingable member released from the pivotal member; and

Figure 6 is a vertical sectional view taken substantially on the plane of section line 6—6 of Figure 2.

Referring now to the drawings in detail, where in for the purpose of illustration, there is disclosed a preferred embodiment of the present invention, the numeral 10 represents a spring operated or spring motor driven alarm including

2

a brake mechanism that comprises a bell crank lever 12 having a locking dog or pawl 14 at one end and an eye 16 at its other end.

A coil spring 18 is anchored at one end to a part of the alarm and the other end of the coil spring 18 is secured to the pawl 14 to urge the pawl from the motor control ratchet 20 of the alarm.

A plunger 22 slidably received in an opening 24 in the alarm is pivoted as at 26 to the eye end of the bell crank lever 12. An abutment 28 is mounted on the plunger 22 and a coil spring 30 embraces the plunger and is biased between abutment 28 and the inner wall of the alarm for urging the plunger inwardly of the alarm and the lever 12 to a brake releasing position.

The alarm is also provided with a finger grip 32 whereby the alarm spring motor M can be placed in tension. When the motor for the alarm is in operation, the finger grip 32 will rotate and a striker 34 will oscillate to strike a bell and sound an alarm.

The particular type of drive mechanism, consisting of a spring motor and gears for oscillating the hammer or striker 34, is not shown, since such drive mechanisms are well known as illustrated in patents numbered 543,896; 298,981; and 428,160.

The alarm 10 is mounted on a support 36 and an elongated channel shaped base member 38 is also mounted on the support 36. The inturned end portions of a substantially U-shaped member 40 extend through the leg portions of a channel shaped swinging member 42 and enter suitable apertures provided in the leg portions of the channel shaped base member 38.

The leg portions of the member 42 are notched, as at 44, to receive the web of the member 40 and the leg portions of the base member 38 are also notched, as at 46, to receive the web of the member 40 when the member 42 is swung inwardly against the base member. The web of the member 42 is provided with a cut-out 48 (see Figure 2) so that the member 42 can swing, without obstruction, relative to the base member.

The leg portions of the base member 38 are provided with registering slots 50 that slidably receive a guide bar 52. A guide pulley 54 is swiveled, as at 56, to the base member and receives a signal operating or actuating line 58. The line 58 is wrapped about the guide bar 52 and is also wrapped about and secured to the web of the U-shaped member 40.

A latch or stop member 60 is pivoted by a pin 62 or the like, to the base member 38 and includes

an offset portion 64 that will bear against the web of the member 42 to hold the member 42 against the base member 38 and the line 58 in tension. A hook or loop 66 is formed at the outer free end of the member 60 and includes a bearing portion 68 that rests against the finger grip 32, see Figure 4, when the portion 64 bears against the web of the member 42. As the finger grip 32 rotates counterclockwise, as shown in Figure 4, the member 60 will gravitate or pivot downwardly so that the portion 64 will ride off the web of member 42 and the member 42 will swing downwardly to relieve the tension in the line 58.

The numeral 10 represents a casing in which there is disposed a fusible element 72. Lines or wires 74 and 76 are fixed to the fusible element 72 and extend outwardly through aperture 78 and 80 provided in the casing 10. The line 74 is anchored to a structural element, such as a ceiling 82 and the line 76 is trained over a pulley 84 mounted on a bracket 86 depending from the support 36 and is secured to the plunger 22. It being understood that the lines 74 and 76 are in tension to move the plunger 22 against action of the springs 30 and 18 and force the pawl 14 into braking engagement with the ratchet 20.

In practical use of the present invention the alarm 10, base member 38, and all parts mounted on the support 36 and the base member are enclosed in a hood 88 mounted on the support 36 and the support 36 is secured to a supporting structure, such as the ceiling 82, in a room area or furnace room.

In response to a high temperature condition about the casing 10, the fusible element 72 will expand or break relieving tension in the line 76 and the springs 18 and 30 will urge the pawl 14 out of braking engagement with the ratchet 20. As the pawl 14 disengages the ratchet 20 the alarm 10 will be sounded and the finger grip 32 will rotate to permit the member 60 to swing downwardly to release the member 42. The member 42 will then pivot downwardly to relieve the tension in the line 58 that extends to a suitable signal or to the plunger 22 of another alarm such as the alarm 10.

Any suitable number of alarms, 10, may be used on the same hook-up and placed in various rooms or in a control room so that an attendant may be informed of high temperature conditions in a known room or rooms.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A signaling device comprising a spring operated alarm having a brake mechanism and a rotatable finger grip that is operatively connected to the spring of the alarm and which will rotate during the sounding of the alarm, means for holding the brake mechanism in a brake applying position, said means including a thermal responsive member, a signal operating line, and means actuated by the finger grip for urging the line to a signal operating position.

2. A signaling device comprising a spring operated alarm having a brake mechanism and a rotatable finger grip that is operatively connected to the spring of the alarm and which will rotate during the sounding of the alarm, means for holding the brake mechanism in a brake applying position, said means including a thermal responsive member, a signal operating line, a support for the alarm, a base member mounted on said support, a pivotal arm carried by the base member and secured to the line, and means carried by the base member and actuated by the finger grip for holding the arm against the base member and the signal operating line in tension.

3. A signaling device comprising a spring operated alarm having a brake mechanism and a rotatable finger grip that is operatively connected to the spring of the alarm and which will rotate during the sounding of the alarm, means for holding the brake mechanism in a brake applying position, said means including a thermal responsive member, a signal operating line, a support for the alarm, a base member mounted on said support, a pivotal arm carried by the base member and secured to the line, and a swingable member mounted on the base member and engaging and holding the arm against the base member and the operating line in tension, said swingable member having a portion bearing against the finger grip, said portion being released from said finger grip as the latter rotates whereby the swinging member releases the arm so that it can swing freely.

4. A safety signal comprising a spring operated alarm having a brake mechanism and a rotatable finger grip that is operatively connected to the spring of the alarm will rotate during the sounding of the alarm, a line for holding the brake mechanism in a brake applying position when the line is in tension, a thermal responsive member connected to the line and responsive to heat for relieving tension in the line, a signal operating line adapted to hold a signal in an inoperative position when the said operating line is in tension, a base member for the alarm, means swingably carried by the base member for holding the signal operating line in tension, and means engaged by the finger grip for releasing said holding means, said last mentioned means including a latch member pivotally mounted on the base member and having a detent engaging the means for holding the line in tension and retaining the holding means against the base member.

5. A safety signal comprising a spring operated alarm having a brake mechanism and a rotatable finger grip that is operatively connected to the spring of the alarm will rotate during the sounding of the alarm, a line for holding the brake mechanism in a brake applying position when the line is in tension, a thermal responsive member connected to the line and responsive to heat for relieving tension in the line, a signal operating line adapted to hold a signal in an inoperative position when the said operating line is in tension, means for holding the signal operating line in tension, a swingable member having a portion contacting the finger grip, said portion being released from said finger grip as the latter rotates whereby the swingable member releases the holding means, said swingable member engaging the holding means when said portion contacts the finger grip, and a base supporting said means and said swingable member, said swingable member holding the means against the base.

6. In a signaling device including a spring operated alarm having a braking mechanism and a rotatable finger grip that is operatively connected to the spring of the alarm and which will rotate during the sounding of the alarm, a fusible member having first and second end portions, means anchoring the first portion of said fusible member to a supporting structure, a connector between the second end portion of said fusible member and said braking mechanism, said connector being in tension and urging the braking mechanism to its brake applying position, an alarm operating line, a base member, means carried by said base member receiving said line and including a pivotal member, a common support for the alarm and the base member, and a swingable latch mounted on the base member engaging and holding the pivotal member against the base member and the line in tension, said latch normally engaging the finger grip and being released from the finger grip moved to release the pivotal member during rotation of the finger grip.

7. The combination of claim 6 wherein said means carried by said base member receiving said line includes a guide member, said base member having a pair of complementary slots slidably receiving said guide member.

8. In combination with a spring operated alarm including a finger grip that is operatively connected to the spring of the alarm and which will rotate during the sounding of the alarm, of a signal operator including a swingable member, a signal operating line adapted to retain a signal inoperative when the said line is in tension, said line being secured to said swingable member, and a latch member engaging and holding the swing-

ing member against swinging movement and the line in tension, said latch member releasing said pivotal member during the rotation of the finger grip to release the swinging member and relieve the tension in the line.

9. A signal actuator comprising a base member, a swinging member pivoted to said base member for movement toward and away from said base member, a latch member also pivoted to said base member for movement toward and away from said base member and having a detent for overlying the swinging member to retain the swinging member against the base member, a guide bar slidably carried by said base member for movement toward and away from the swinging member, a signal operating line wrapped about the guide bar and attached to said swinging member, said line being in tension to pull the pin toward the swinging member when the swinging member underlies said detent, and means holding the latch member against swinging movement and the detent against the swinging member.

ALBERT O. KJELDERGAARD.
